EMIL GATHMANN, OF BALTIMORE, MARYLAND

INGOT MOLD

Application filed January 16, 1933. Serial No. 652,064.

This invention relates to metallic ingot molds, and particularly to molds having a matrix the horizontal cross section of which will produce ingots of a generally rectangular contour such for example as illustrated and described in U. S. Patent 1,892,569 issued to me December 27, 1932.

As is well known to those familiar with the art, when molten steel is poured into metallic ingot molds, it solidifies through the formation of dendritic and free or equiaxed crystals. The molten ingot metal immediately adjacent the mold walls and in contact therewith is cooled very rapidly and crystallizes in the form of dendrites, which grow into the mother liquid at substantially right angles to the mold matrix, while the remainder of the ingot is composed of free or equiaxed crystallization. The ratio of the depth of the ingot metal comprising dendritic crystalline structure to the minimum cross sectional width of the ingot depends upon such factors as the mold temperature and pouring temperature, the rate of teeming, and the size and contour of the ingot being formed. With proper mold and pouring temperatures and correct teeming, the maximum depth of the zone of dendritic crystallization is from one sixth to one fifth of the minimum cross section of the ingot in ordinary killed steels.

As explained in considerable detail in my Patent 1,892,569, the primary corners of an ingot of the contour described in said patent break contact with the mold chamber walls soon after the formation of the initially solidified, relatively thin ingot skin, due to the differential shrinkage of the ingot in the mold (i. e., the ingot contracting in cross section and the mold expanding in cross section), and the dendritic or chill crystals do not extend as far inwardly at the primary corners of the ingot as they do adjacent the curved portions of the primary sides of the ingot. Macroscopic studies of etched cross sections of ingots of the type shown and described in this patent produced in commercial practice have disclosed that at the primary corners of such an ingot the dendritic crystals extend inwardly a distance equal to only about one-twentieth of the minimum cross

section of the ingot as against one sixth to one fifth at the central portions; and I have found that, for this reason, the radii of the primary corners of the ingot need not be so great as the radii of the other outwardly curved portions of the ingot surface. By virtue of this fact, it is possible to employ a relatively small curvature at the primary corners, thus providing a contour adapted to most efficient reheating and rolling, and at the same time locating the foci of the radii forming the primary corner walls within the zone of free or equiaxed crystals so that there is little or no danger of the formation of so-called cleavage planes. It is most important that the radii forming the primary corners be not too large; otherwise the ingot corners may crack vertically during reheating and laps and tears may occur during the reduction of the ingot to blooms, slabs, and so forth. To satisfy the requirements for best reheating and rolling properties as well as the requirements of crystallization in the ingot necessitates that the curvature of the corners of the solidified ingot be controlled rather exactly, this being a basic principle upon which the present invention is founded.

It is well established practice to make allowance for shrinkage of an ingot amounting to about one eighth inch per foot of ingot cross section. I have discovered that, in order to produce an ingot having primary corners described by radii of a predetermined length relative to the minimum cross sectional dimension of the ingot, such for example as disclosed in my Patent 1,892,569, the corner radii in the metallic mold matrix must be considerably greater than the radii desired in the ingot when it is ready for the reduction process. From tests made, I have found that a mold provided with primary corner radii having a length of between one eighth and one eighteenth of the minimum cross section of a mold matrix of my contour will produce a solidified ingot having primary corner radii between one tenth and one twentieth of the minimum cross section of said ingot.

Accordingly, an object of my present invention is to provide a mold matrix of such cross sectional contour that the arcs defining

the concave portions of the mold matrix at the primary corners will produce ingots substantially within the limits specified in my aforesaid Patent 1,892,569.

5 The invention may be embodied in any type of vertical mold, having big-end-up, ⁷⁰ big-end down, or parallel chamber walls.

In the drawing:

10 Figure 1 is a longitudinal cross sectional view of a mold having a contour in accordance with the present invention.

Figure 2 is a horizontal cross sectional view taken on lines 2—2 of Figure 1.

15 Figure 3 is a fragmentary view on an enlarged scale showing graphically in horizontal cross section the relative relation between the radii of the arcs defining the primary corners of a mold matrix and the radii of the arcs defining the primary corners of a solidified ingot produced therein.

For purpose of illustration, a mold M of the big-end-up Gathmann type, necked in at the bottom as at 1, is shown in Figure 1.

20 The preferred contour of the cross section 25 of the mold matrix in accordance with the present invention is shown in Figures 2 and 3 of the drawing, from which it will be noted that the horizontal cross section of the mold matrix is of generally rectangular contour 30 and is defined by four primary sides 2, each side being connected to an adjacent side by outwardly arched primary corners 3 by means of secondary corner portions 4 preferably of inwardly arched contour. Outwardly 35 arched salients 5 flank and merge with and form a part of the primary sides 2 and preferably are subtended by angles α of less than sixty degrees, the foci of the radii 6 forming said salients 5 lying well within the zone of 40 free crystallization. The relative extents of the zones of dendritic and free or equiaxed crystals forming the ingot structure are shown graphically as merging one with the other by means of dotted lines X in Figure 3 45 of the drawing. For the reasons explained in my Patent 1,745,089, of January 28, 1930, it is desirable that the primary sides 2 be given an inwardly curved contour and that these sides be relatively narrow as compared 50 to the cross section of the ingot.

From deduction and tests made and through the observation of the production of many commercial ingots of the type shown in my Patent 1,892,569 before mentioned, I have 55 determined that an ingot of this contour contracts and frees itself from the mold substantially as shown in Figure 3. An annular space or air gap S begins to form soon after the ingot is cast, and is widest at the primary 60 corners 3' of the ingot, resulting, through the formation by free crystalline contraction, in corner radii 7' at the corners of the solidified ingot which are smaller than the radii 7 of the corners 3 of the mold matrix in which the 65 ingot was cast. Figure 3 graphically shows

the decrease in length by shrinkage of the radius 7 forming the corner of the mold matrix and which was momentarily the radius of the ingot corner 3'. As stated, this shrinkage of the primary corners is materially ⁷⁰ greater than the well known shrinkage in the body of the ingot. For example, if the horizontal cross section b of the mold matrix is made twenty inches and the primary corners 3 are generated by radii 7 measuring ⁷⁵ two inches, the ingot I, during solidification, will assume at its corners 3' a radii 7' measuring about one and five eighths to one and three quarters inches.

I have found it necessary, therefore, to ⁸⁰ design and make the radii 7 defining the primary corners 4 of the mold matrix definitely larger than that desired in the finished or solidified ready-for-rolling ingot of this type. The radii 7 of the mold corner walls should ⁸⁵ be between one eighth and one eighteenth of the length of the cross section b of the ingot and preferably about one tenth as long as the cross section b. Thus, in designing a mold in accordance with the present invention, I lay out the walls, exclusive of the corners, to conform substantially to the shape of the ingot to be produced, and lay out the rounded corner walls 3 with radii 7 longer ⁹⁰ than the corner radii 7' desired in the cast ⁹⁵ ingot. In other words, in making the mold, the walls thereof exclusive of the corner walls are shaped to conform substantially to the shape of the ingot, whereas the corner walls of the mold are shaped to radii longer than ¹⁰⁰ the predetermined corner radii of the ingot to be produced.

In my beforementioned Patent 1,892,569, I have disclosed and claimed ingots of specific contours having primary outwardly ¹⁰⁵ arched corners, the radii of which have a length of less than one tenth but greater than one twentieth of the minimum cross sectional dimension of the ingot. According to the present invention, which relates specifically to the cross sectional contour and relative dimensions of the contour of the mold matrix, the radii 7 of said outwardly curved primary corners 3 of the mold matrix are of a length less than one eighth but ¹¹⁰ greater than one eighteenth of the minimum cross sectional dimension of said mold matrix, and the arcs defining said outwardly curved primary corners 3 are subtended by angles C materially greater than ninety degrees but preferably not more than one hundred degrees and in most cases about ninety-five degrees. Within the proportional dimensions of the cross section of the mold matrix herein shown and described, I am ¹¹⁵ enabled definitely to produce ingots of a cross sectional contour substantially as shown and claimed in my Patent 1,892,569, of December 27, 1932. In producing ingots according to this invention, I confine portions ¹²⁰ 125

of the body of molten metal by mold wall retaining surfaces which, exclusive of the corners, correspond to the contour of the ingot to be produced, and confine intervening 5 corner portions of the molten body by arcuate mold wall retaining surfaces interposed between and connecting said first named surfaces and being of larger radii than the desired predetermined corner radii of the ingot 10 to be produced.

I claim:

1. A metallic ingot mold having a vertically extending ingot forming chamber of generally rectangular cross section, having 15 four sides, at least two opposed sides each including an inwardly arched portion and a pair of outwardly arched portions flanking said inwardly arched portion, the radii of said outwardly arched portions being at least 20 one sixth of the minimum cross section of the mold matrix and four outwardly arched primary corners respectively intervening between and connecting adjacent sides, the radii of said primary corners being less than one 25 eighth but greater than one eighteenth of the minimum cross sectional dimension of the mold matrix.

2. A metallic ingot mold having a vertically extending ingot forming chamber of generally rectangular cross section, the matrix having four sides, at least two opposed sides each including an inwardly arched portion and a pair of outwardly arched portions flanking said inwardly arched portion, the 30 radii of said outwardly arched portions being at least one sixth of the minimum cross section of the mold matrix, and four outwardly arched primary corners respectively intervening between and connecting adjacent 35 sides, the radii of said primary corners being less than one eighth but greater than one eighteenth of the minimum cross sectional dimension of the mold matrix and the arcs defining said primary corners being subtended 40 by angles materially greater than ninety degrees.

3. A metallic mold having a vertically extending ingot forming chamber of generally rectangular cross section defined by four primary sides, at least two opposed sides each including an inwardly arched portion and a pair of outwardly arched portions flanking said inwardly arched portions, the radii of said outwardly arched portions being at least 45 one sixth of the minimum cross section of the mold chamber, and four outwardly arched primary corners respectively intervening between and connecting adjacent sides, the radii of said primary corners being equal to approximately one tenth of the minimum cross sectional dimension of the mold matrix.

In testimony whereof, I have hereunto subscribed my name.
